Primary Examiner — Wendy L Arminio(74) *Attorney, Agent, or Firm* — Hinckley, Allen & Snyder, LLP; Stephen Holmes(57) **CLAIM**

The ornamental design for a dispensing head, as shown and described.

DESCRIPTION

FIG. 1 is a perspective view of a dispensing head in accordance with the present design, shown in an environment of use on a product container drawn in broken lines; FIG. 2 is a rear perspective view thereof; FIG. 3 is a top view thereof; FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines illustrating a product container depict environment and form no part of the claimed design. All other broken lines depict portions of the dispensing head that form no part of the claimed design.

1 Claim, 7 Drawing Sheets(56)
